SANITARY MEANS OF EMPTYING VACUUM
CLEANER BAGSPhilip Gasner and Sigmund Gasner, Brooklyn,
N. Y., assignors to Sidney Gasner, Brooklyn,
N. Y.

Application April 17, 1939, Serial No. 268,351

3 Claims. (Cl. 183—51)

This invention relates to improved sanitary means for removing dust from a vacuum cleaner bag.

The principal object of this invention is to provide a novel construction for extending the dust collecting receptacle away from the inlet duct of the vacuum cleaner bag so that the dust may be efficiently removed from the vacuum cleaner bag without removing said bag from the vacuum cleaner.

Another object of the invention is the provision of an improved form of a disposable throw-away paper bag which may be used in cooperation with the vacuum cleaner bag to remove the contents thereof.

Another object of the invention is the provision of a vacuum cleaner bag having means adapted to secure thereto a pair of pedal members which are employed to facilitate the removal of the contents of said bag.

Another object of the invention is the provision of a vacuum cleaner bag of novel construction so that said bag may be maintained in an upright and fully opened position whenever it is desired to dispose of the contents of said bag.

Other objects of our invention will be set forth in the following description and drawings, which illustrate preferred embodiments thereof, it being understood that the above statement of the objects of our invention is intended generally to explain the same without limiting it in any manner.

Fig. 1 is a front elevational view of a vacuum cleaner bag with the throw-away paper bag attached thereto, partially broken away.

Fig. 2 is a side view thereof.

Fig. 3 is a sectional view on line 3—3 of Fig. 1.

Fig. 4 is a side view, showing the vacuum cleaner bag and throw-away bag partially broken away.

Fig. 5 is a sectional view on line 5—5 of Fig. 1 showing the clamping member partly withdrawn.

Fig. 6 is a perspective view of the clamping member.

Fig. 7 is a perspective view of the throw-away paper bag.

Fig. 8 is a front elevational view of the vacuum cleaner bag with the throw-away bag attached thereto, showing a different type of clamping means, partially broken away and partially in section.

Fig. 9 is a side view of Fig. 8, the throw-away bag being partially broken away to illustrate the clamping means.

Fig. 10 is a sectional view on line 10—10 of Fig. 8.

Fig. 11 is a side view with the throw-away bag removed from the vacuum cleaner bag.

Fig. 12 is a front view of the vacuum cleaner bag, showing a pedal member attached thereto, the vacuum cleaner bag being shown broken away.

Fig. 13 is a side view of the vacuum cleaner bag showing the pedal members attached thereto.

Fig. 14 is a perspective view of one of the pedal members.

Referring to the drawings, more particularly to Fig. 1 thereof, the reference letter 1 represents the vacuum cleaner bag or dust collecting receptacle. It will be noted that a greater portion of the upper part of the vacuum cleaner bag has been broken away for the convenience of illustration. Said bag 1 is provided with an inlet duct 2 having a coupling 20 adapted to removably secure said duct to the vacuum cleaner casing. Fastening means 21, more specifically in this instance hookless fastener elements are provided on the face of the bag 1 adjacent duct 2 and are adapted to mesh or lock with corresponding fastener elements on the outer surface of said nozzle. The purpose of this construction is to enable the bag 1 to be substantially extended away from the vacuum cleaner or sweeper itself as will be hereinafter more fully explained.

The bottom edge of bag 1 is provided with a relatively stiff edging 5 along two opposite edges of the bottom of said bag. Bag 1 is normally kept in open position by means of a pair of hinges 3 secured to the sides of the bag 1 whose lower edges are not provided with stiff-edging members 5, said hinges being kept in extended position by means of springs 4. It will be noted that when the lower part of bag 1 is in the completely opened position, the mouth of said bag assumes a square shape so that a considerable opening is provided for the removal of the dust from said bag.

In order to close the bottom of bag 1, the marginal edgings 5 are brought towards each other, and the hinges 3 folded inwardly thus collapsing the bottom of bag 1 in the form of a bellows construction. A clamp member 6 is then slipped over the collapsed bottom of the bag and retains the same in a closed position. Clamp 6 is provided with a hook member 7 so that said clamp may be manipulated with facility.

A throw-away bag 8 made of paper or any other suitable inexpensive material for disposing of the dust may be used in connection with the vacuum

cleaner bag 1 in the manner shown in Figs. 1 and 2. The throw-away bag 8, illustrated in Fig. 7, consists of a paper bag having a pair of aligned holes 9 located in the front and back faces thereof. An opening 13 having a flap 14 is located at the intersection of the side wall and front wall of bag 8. The purpose of flap 14 will be hereinafter explained.

In order to secure throw-away bag 8 to bag 1, strip members 10 are sewn to the front and back walls of said bag. A female snap element 11 is secured to the free end of each strip 10. Adjacent said female members 11 and secured to the bag 1 are male snap members 12.

15 The method of emptying the contents of bag 1 without removing said bag from the vacuum cleaner is as follows:

16 Hookless fasteners 21 are separated thus enabling the bag 1 to be substantially extended away 20 from inlet duct 2. Throw-away bag 8 is then slipped over the lower part of bag 1 so that holes 9 are fitted over male fastening members 12 and the female fasteners 11 are snapped thereon. Clamp 6 is withdrawn through opening 13 of 25 throw-away bag 8 by pulling hook 7 of said clamp through window 13. Bag 1 will snap into the fully opened position shown in Fig. 3 due to the opening action of hinges 3. In order to prevent the escape of any dust through window 13, flap 30 14 which is provided with any suitable adhesive on its inner face is then folded over to completely seal window 13. Bag 1 is then agitated or shaken until the entire contents thereof fall into throw-away bag 8. It will be obvious that the dust may 35 be readily, efficiently and sanitarily disposed of by our improved method and means.

40 Figs. 8, 9, 10 and 11 illustrate a different clamping means than that heretofore described. As clearly shown in Fig. 11, a resilient S-shaped member 16 is pivotally connected to one of the metal edgings 5 by means of pin 17.

45 The use of a vacuum cleaner bag having clamping means of this type dispenses with the need for a window in the throw-away bag. The throw-away bag 8 is connected to bag 1 as previously described and by exerting pressure on arm 22 of clamp member 16, said member 16 will spring open and bag 1 will snap into open position. The

dust may then be shaken into the throw-away bag.

5 Figs. 12, 13 and 14 illustrate additional means which may be used in combination with our improved vacuum cleaner bag for emptying the 10 contents thereof. As shown in Fig. 14, a pedal member 18 of angular shape and made of fibre board, cardboard or any suitable inexpensive semi-rigid material is employed. Said pedal member is provided with an opening 19. As 15 shown in Fig. 13, pedal members 18 are removably connected to bag 1 by fitting holes 18 over male fastening members 12 and then locking the female fasteners 11 thereon. The person then 20 steps upon each pedal member 18 and shakes bag 15 1 so that the dust may be completely removed therefrom. When pedal members 18 are employed, it is not necessary to use any throw-away bag.

25 We have shown preferred embodiments of our invention, but it will, of course, be understood that other modifications, alterations, omissions and changes may be made without departing from the spirit and scope of the invention.

We claim:

1. In combination, a dust collecting receptacle having an inlet duct and a discharge end, clamping means for opening and closing said discharge end, a throw-away bag removably secured to said discharge end, said throw-away bag completely enclosing said clamping means.

2. A throw-away bag for use in combination with a dust collecting receptacle for vacuum cleaners, said throw-away bag having holes in the front and rear walls thereof adapted to receive 35 securing means on said receptacle for removably securing the same thereto, and an opening at the side thereof adapted to permit withdrawal of the member closing the discharge opening of said receptacle, and a flap adapted to cover said opening, after the said closing member is withdrawn.

3. The combination as claimed in claim 1, in which the clamping means is adapted to be operated while the throw-away bag is covering the same.

45 PHILIP GASNER.
SIGMUND GASNER.
